UNITED STATES PATENT OFFICE

KARL KLEIN, OF ST. LOUIS, MISSOURI

ELECTRICAL INSTRUMENT

Application filed July 23, 1928. Serial No. 294,829.

This invention relates to improvements in electrical instruments, and consists in the novel construction hereinafter disclosed.

This application is a continuation in part 5 of my copending application Serial No. 174,901, filed March 12, 1927, for combined voltmeter and ammeter.

An object of the invention is to provide an electrical instrument designed to be connected 10 into an electric circuit to indicate the voltage and amperage on concentric dials supported by a common case.

Another object of the invention is to provide a combined voltmeter and ammeter in 15 which the dials are arranged on concentric axes, and the indicators or pointers of which are concentrically mounted, in combination with means for actuating the pointers to indicate the voltage and amperage of the current 20 passing over the circuit into which the instrument is connected.

Additional advantages of the construction will be apparent from the following detailed description thereof taken in connection with 25 the accompanying drawing, in which

Fig. 1 is a front elevation of the instrument.

Fig. 2 is a vertical section through the instrument.

Fig. 3 is a vertical section at right angles to 30 Fig. 2.

Fig. 4 is a diagrammatic view illustrating the electrical connections and the operative parts of the instrument.

In the embodiment of the invention illustrated in the drawing, the device is shown as including a case comprising a cylindrical metallic wall 1 joined at one end by a back wall 2, said metallic case being covered by an exterior case 3 of insulating material. The metallic case is internally lined by a side wall 4, a back wall 5, and a front wall 6, said walls 4, 5 and 6 also being of insulating material. The interior of the case is also divided into an upper and lower chamber 7 and 8, respectively, by a transverse partition wall 9, which is preferably of a nonmagnetic or insulating material.

The front of the case is provided with a panel 10 of glass or other transparent material, said panel 10 being held in adjustment by

a rim 11 that threads into the wall 1. A spacing ring 12 is disposed between the panel 10 and the wall 6, and the joint between the panel 10 and the rim 11 may be sealed by a gasket 13, if desired, to prevent dust or dirt 55 from entering the instrument case.

Upon the outer face of the wall 6 are two concentric arcuate dials 14 and 15, the upper one of which is graduated for voltage indications, and the lower one of which is graduated 60 for amperage indications.

Within the chamber 7 is a coil 16 of low resistance material, said coil being connected at one end to a binding post 17 that is insulated by an insulating bushing 18 from the 65 case. A lead 19 extends from the binding post 17 to the coil. The binding post 17 is arranged for exterior connection with one lead 20 of an electric circuit. The opposite end of the coil 16 is connected with a binding post 21 which post 21 has electrical contact with the metallic wall 1. The binding post is arranged for connection with an extension 22 of the lead 20, the coil 16 therefor being in series with the source of power for energizing the 75 lead 20.

Arranged within and cooperating with the coil 16 is an armature 23 which is raised and lowered by the current traversing the coil 16 co-ordinate with the current voltage, it being understood that the action of the armature in the coil is the usual action of a solenoid. The armature 23 has connected with its lower end a rack bar 24 of nonmagnetic material. The armature is normally actuated downwardly by a contractile spring 25 connected at one end to a pin 26 carried by the bar 24 and at the other end to a permanent stationary part of the case. As illustrated, the lower end of the spring is connected to a guide plate 27 for the bar 24. Above the partition 9 it is also preferable to provide a second guide plate 28, so as to preserve the bar in vertical alinement. The bar 24 has its lower end formed to provide a rack 29, which meshes 90 with a pinion 30 carried on a sleeve 31. The pinion 30 is connected to a pointer 32 which indicates the position of the armature 23.

The sleeve 31 extends through an opening 33 in the wall 6, which opening constitutes a bearing for said sleeve. The sleeve is provided with a flange 33 that seats against the rear 100

edge of the opening 32, said sleeve extending forwardly of the wall 6 into the space between said wall and the panel 10. The forward end of the sleeve carries a pointer or indicator 34 which coordinates with the dial 15, it being understood that the sleeve 31 is rocked through the rack and pinion connection when the armature 23 is raised by the influence of the current traversing the coil 16. Since the extent of movement of the armature, and therefore the bar 24, is coordinate with the amperage of the current traversing the coil 16, a direct reading of the amperage will be translated and indicated through the connections just described, so that an accurate indication of the amperage is provided by the position of the pointer 34 in relation to the dial 15.

In the lower part of the case is located the mechanism for indicating voltage. This mechanism comprises a coil 35 of high resistance material, which coil is electrically connected with the case 1 by a bar 36, the current therefor flowing from the binding post 21, which is electrically connected with the lead 20, enters the coil 35 through the bar 36. The opposite end of the coil 35 is connected with a binding post 37 which is insulated from the case by an insulating bushing 38, said binding post being arranged for exterior connection with the opposite line 39 of the main circuit. The coil 35 therefore is connected in parallel with the main circuit leads. A permanent magnet 40 is supported by the wall 5 in such position that the ends thereof lie within the field of the coil 35. Located within the terminals of the magnet 40 is an armature 41, preferably of soft iron, said armature being directly carried by a spindle 42 which extends rearwardly and forwardly from the armature. The rear end of the spindle is journaled in a thimble bearing 43 in the wall 5, and the forward end of said spindle extends through the sleeve 31 to a point forward of the front extremity thereof. The spindle 42 carries at its forward extremity a pointer or indicator 44, which is of slightly greater length than the indicator 34, said pointer 44 co-ordinating with the dial 14 for voltage indications. The spindle 42 is normally held at the point of rest by a coil spring 45 connected at one end to a stationary part of the case (as illustrated, to the wall 5) and at the other to the spindle 42.

The armature 41 is held in balance at the point of rest by the magnetic force of the permanent magnet 40 operating in opposition to the spring 45. When the current traverses the coil 35, a field of force is set up which reacts with the field of force produced by the permanent magnet 40, thereby tending to rotate the armature in coordination with the voltage of the current traversing the coil 35. The extent of movement of the armature

is calibrated with the volt indicating dial and, therefore, a direct positive reading of the voltage is accomplished by the extent of movement of the indicator 44 on the dial 14.

From the foregoing it will be seen that I have combined in a single instrument a voltmeter and an ammeter, the registrations of both of which are readily observable at the same time, so that the desired information afforded by use of these two instruments may be quickly obtained. The construction and relationship of the parts may be varied within equivalent limits without departure from the nature and principle of the invention.

What I claim and desire to secure by Letters Patent is:—

1. An electric instrument of the class described comprising a case separated into non-conducting compartments, dials carried in the case and visible through one wall thereof, a pair of indicators cooperating respectively with said dials, said indicators being co-axially alined, an electric actuator responsive to amperage located in one of said compartments for operating one of said indicators, and an electric actuator responsive to voltage located in the other of said compartments for actuating the other of said indicators.

2. An electric instrument of the class described comprising a case, dials carried in the case and visible through one wall thereof, a pair of indicators cooperating respectively with said dials, said indicators being coaxially alined, a bar supported in and slidable within the case, a rack and pinion connection between the bar and one of said indicators, an armature carried by said bar, a coil energized by a main electric circuit and cooperating with said armature to actuate said bar and thereby the indicator connected therewith, an armature, a permanent magnet cooperating with said armature, connections between the armature and the other indicator, and a coil associated with said armature energized by an electric circuit whereby said armature is deflected to operate said indicator.

3. An electric instrument of the class described comprising a case, a pair of indicator shafts coaxially alined and supported in the case, a pair of cooperating concentric dials coordinating respectively with said indicators, a slideable bar mounted in the case, a spring normally actuating the bar to one position, an electric means for moving said bar connected in series with a circuit, said means being responsive to amperage of the circuit, connections between the bar and one indicator shaft for moving the indicator responsive to amperage, and a second electric means connected with a circuit responsive to voltage, said means being adapted to rotate the other indicator shaft to indicate voltage.

KARL KLEIN.
